UNITED STATES PATENT OFFICE.

AMERICO NASSANO, OF SAN FRANCISCO, CALIFORNIA.

METHOD OF SEALING ENVELOPS.

1,387,164.

Specification of Letters Patent. Patented Aug. 9, 1921.

Application filed August 16, 1919. Serial No. 318,034.

To all whom it may concern:

Be it known that I, AMERICO NASSANO, a citizen of the United States, residing at San Francisco, in the county of San Francisco, State of California, have invented certain new and useful Improvements in Methods of Sealing Envelops; and I do declare the following to be a full, clear, and exact description of the same, reference being 10 had to the accompanying drawings, and to the characters of reference marked thereon, which form a part of this application.

This invention relates to a method of sealing envelops, the principal object of the invention being to so seal an envelop that it cannot be opened by any party other than the one for whom it is intended without the knowledge of the owner when he finally receives it.

20 In the common form of gummed-flap envelops, it sometimes happens that unscrupulous persons will open the envelop by steaming the gummed-flap, read the contents of the envelop or extract some article of value 25 therefrom, after which they can again seal the flap without danger of detection.

With my improved method of sealing envelops, this is impossible. Furthermore, I may do away with the gumming of the flap, 30 with the attendant injurious practice of moistening the same with the tongue, and I may also discard the flap itself, except that it aids in keeping dust and dirt from the interior of the envelop, and very small 35 articles from falling out.

The range of my invention also includes the sealing or securing of the contents of an envelop within the same, in combination with or independently of the actual sealing 40 of the envelop itself, so that even if an envelop were opened, the contents thereof could not be examined and replaced without the rightful owner of the missive being aware that the same has been tampered with.

45 These objects I accomplish by means of such structure and relative arrangement of parts as will fully appear by a perusal of the following specification and claims.

On the drawings similar characters of reference indicate corresponding parts in the 50 several views.

Figure 1 is a perspective view of the back of an envelop showing the same sealed by my improved method.

55 Fig. 2 illustrates the method as applied

to fasten or seal the ends of a letter or note without the use of an envelop.

Fig. 3 is a fragmentary enlarged plan showing the form of cuts made in the thicknesses of the envelop as the first step in my 60 improved method of sealing the same.

Fig. 4 is an enlarged fragmentary cross section of an envelop showing the completed sealing.

Referring now more particularly to the 65 characters of reference on the drawings, the numeral 1 denotes an envelop having the usual flap 2 on one end thereof.

My improved method of sealing the flap to the other thicknesses of the envelop consists of first preferably cutting a plurality of very short radiating lines 3—say $\frac{1}{16}$ inch long—through such thicknesses, without removing any of the paper, then bending such V-shaped cut portions 4 so that they project outwardly from the surface of the envelop on either side, and then flattening down these cut portions onto the outer surface of the envelop as shown at 5.

It will thus be seen that the three thicknesses of the envelop at the point where the flap overlaps the envelop proper are united together in such a manner that when pulled apart, they cannot again be united in the same way without it being evident that the 85 envelop has been tampered with.

The slits 3 can be cut and the flattening operation performed in any desired manner, as for instance with the aid of a punch having a star-shaped cutting edge.

90 Certain machines now on the market for pressing little metal rings through numerous pages of documents to hold the same together could also be easily adapted for my purpose with a few slight changes.

If desired to seal the contents of the envelop therein, the contents are first inserted in the envelop and the same operation gone through as in the case of sealing the envelop, this operation being preferably accomplished at the opposite end of the envelop from the flap.

In order to definitely locate such point of sealing for the sake of uniformity, a small orificed seal such as 6 may be secured to 105 the envelop at that point, the punching tool being inserted through the hole in the seal as a guide.

If desired to send notes, etc., short distances by messenger, etc., without the neces-

110

sity of inclosing them in envelops, the mis-
sive may be folded as many times as may be
desired as at 7 and any of the outer edges
then sealed together by my improved
5 method.

From the foregoing description it will be
readily seen that I have produced such a
device as substantially fulfills the object of
the invention as set forth herein.

10 While this specification sets forth in de-
tail the present and preferred construction
of the device, still in practice such deviation
from such detail may be resorted to as do not
form a departure from the spirit of the in-
15 vention, as defined by the appended claims.

Briefly my invention consists in symmetri-
cally slitting the superposed plies of paper
in such manner as to form a plurality of
free, outwardly bendable tongues, and then
20 doubling collective tongues, back over the
contiguous face of a ply, so as to clench the
plies together and form an original inter-
lock.

Having thus described my invention what
25 I claim as new and useful and desire to se-
cure by Letters Patent is:

1. A method for securing superposed plies
of flexible material together without any ex-
traneous appliances, which consists of slit-
30 ting the superposed plies to form a plurality
of tongues about a common point, then bend-

ing collective tongues from said point, and
folding them down over the contiguous face
of one ply.

2. A method for securing plies of material 35
together in such manner as to indicate hav-
ing been separated after the initial fasten-
ing, which consists in forming a plurality
of tongues in collective groups by slitting
the material about a common point, and then 40
creasing the groups of tongues outwardly
over a face of one of the plies.

3. A method for securing plies of mate-
rial together in such manner as to indicate
having been separated after the initial fas-
tening, which consists in forming a plurality
45 of tongues in collective groups by radially
slitting the material about a common point,
and then creasing the groups of tongues out-
wardly over a face of one of the plies. 50

4. A plurality of plies of flexible material
having groups of superposed integral
tongues, arranged radially about a common
point, the groups each being foldable and
55 clenched and holding the plies in assembled
relation.

In testimony whereof I affix my signature
in presence of two witnesses.

AMERICO NASSANO.
